UNITED STATES PATENT OFFICE.

JACOB T. ALDERSON AND SUE F. ALDERSON, OF SUTHERLIN, VIRGINIA.

VERMIN-DESTROYER FOR FOWLS.

1,234,111.

Specification of Letters Patent. Patented July 24, 1917.

Application filed July 3, 1916. Serial No. 107,439.

To all whom it may concern:

Be it known that we, JACOB T. ALDERSON and SUE F. ALDERSON, citizens of the United States, and residents of Sutherlin, in the 5 county of Pittsylvania and State of Virginia, have invented certain new and useful Improvements in Vermin - Destroyers for Fowls, of which the following is a specification.

10 The present invention relates to poultry cleaning devices and more particularly to new and useful improvements in vermin destroyers.

15 The primary object of our invention is to provide a vermin destroyer for cleaning poultry and the like, whereby lice and other vermin may be either destroyed or caused to leave the fowl treated.

20 Another object of our invention is to provide a device of the character described which is adapted to restrain a fowl during the treating process, which preferably consists of smoking the body of the fowl with a vermin destroying compound or the like.

25 A further object of our invention is to provide a device of the character described which is adapted to restrain a fowl in the presence of a heavy smoke or vermin destroying vapor, means being provided 30 whereby the head of a fowl is kept immune from the vermin destroying vapor to prevent smothering of the fowl.

35 A still further object of our invention is to provide a device of the character described which is simple in construction, strong and durable, cheap to manufacture and effective in operation.

40 Other objects and advantages to be derived from the use of our improved vermin destroyer will appear from the following detail description and claims, taken with an inspection of the accompanying drawings, in which:

45 Figure 1 is a perspective view of a vermin destroyer embodying the improvements of our invention shown at a right angle to its position of use;

Fig. 2 is a longitudinal sectional view of the same;

50 Fig. 3 is a vertical sectional view taken on the line 3—3 of Fig. 2;

Fig. 4 is a horizontal sectional view taken on the line 4—4 of Fig. 2; and

55 Fig. 5 is an enlarged transverse sectional view of the smoke outlet chamber.

Referring more particularly to the draw-

ings, wherein similar characters of reference designate like and corresponding parts throughout the various views, 1 designates in its entirety the body or smoke chamber 60 of our improved vermin destroyer, the same having a top 2, bottom 3, side walls 4, a rigid end wall 5 and a partition 6. The partition 6 is provided with an elliptical opening 7 having an annular flange 8 formed adjacent 65 thereto. A wire frame 9 is carried by the flange 8, said frame being semi-elliptical in cross section and being adapted to receive a fowl. Of course, we do not limit ourselves to the particular construction of frame 70 shown, since this frame may be made of woven wire or mesh screen. However, the frame is provided with side openings 10 relatively larger than the other openings in the frame to accommodate the wings of the 75 fowl.

A pair of straps or similar flexible elements 11 and 12 extend transversely across the opening 7, said straps being connected by vertically extending bars 13, said bars 80 being slightly curved. Buckles 14 are provided in the straps 11 and 12 for adjusting the same to fowls of various sizes. The straps 11 and 12 are doubled upon themselves and pass through openings formed in 85 the flange 8 as indicated at 15 in Figs. 2 and 4.

A closure 16 is hinged at 17 to the bottom wall 3 of the housing 1, said closure having a flanged opening 18 for accommodating the 90 head of the fowl. A hasp 19 is carried by the upper end of the closure 16, said hasp being engageable with a staple 20 carried by the top wall 2 of the chamber 1.

A handle 21 is mounted on the top wall 95 2 for transporting the device from place to place. An outlet or draft creating member is provided and is in the form of a rectangular extension 22 mounted on the top wall 2, said extension communicating with the 100 smoke chamber by virtue of the apertures 23 formed in said wall 2. A regulating member 24 is mounted in the outlet member 22, said member 24 having a handle 25 thereon. The outlet member 22 is riveted 105 or otherwise secured to the top wall 2 as indicated at 26 adjacent the rear end of the body 1. The regulating member 24 is adapted to snugly move within the outlet member 22, this snug engagement being best 110 shown in Fig. 5 at 27.

In use a slow burning or smoldering fire

is made in the smoke chamber 1, a fire door 28 being provided for permitting access to the interior of the chamber 1. The fuel of which the fire is made may consist of red hot 5 coals with tobacco placed thereon. The fowl is placed in the frame 9 and the closure 16 moved to the closed position. The draft controlling device 24 may be slightly opened as shown in Figs. 1 and 2 to permit the fire 10 to start. However, when a smoke of desired density has been created the member 24 should be moved to the closed position, thereby preventing the fire from burning 15 with a flame and insuring a smoldering smoke creating fire. If desired a vermin destroying smoke may be created by saturating a cloth in sulfur and lighting the same, after which the chamber is to be closed.

Of course, it is to be understood that we 20 do not limit ourselves to the use of the device as a vermin destroyer for fowls and the like, since the same might be used for animals of all kinds. To adapt the device for 25 various kinds of animals it would be only necessary to change the shape of the receiving frame and to arrange the head opening 18 at different points.

From the above description taken in connection with the accompanying drawings, 30 it is thought that a clear and comprehensive understanding of the construction, operation and advantages of our invention may be had, and while we have shown and described the device as embodying a specific 35 structure, we desire that it be understood

that such changes may be made in said structure as do not depart from the spirit and scope of the invention as claimed.

Having thus fully described our invention, what we claim as new and desire to 40 secure by Letters Patent, is:—

1. The combination with a casing having a hinged cover at one end, of a partition extending transversely across the receptacle, the hinged cover having an inwardly extending flanged portion providing an opening, said partition being provided with an inwardly extending flange forming an opening therein, an animal receiving cage formed of reticulated material having its ends secured to the last-mentioned flange, flexible elements connecting with the cage for engagement with the back of the animal, and parallel bars connecting the flexible elements and also for engagement with the back of 50 the animal.

2. The combination with a casing having a hinged cover at one end thereof, of a partition extending transversely across the receptacle and having a relatively large opening therein, an animal receiving cage formed from reticulated material having its ends secured to the partition at the edges of the opening, and means carried by the cage adapted to be engaged with the animal. 60

In testimony whereof, we affix our signatures hereto.

JACOB T. ALDERSON.
SUE F. ALDERSON.
